HINGE CONSTRUCTION

Wilbert C. Buescher, Alhambra, Calif., assignor
to General Controls Co., Glendale, Calif., a
corporation of California

Application November 24, 1947, Serial No. 787,747

5 Claims. (Cl. 220—31)

1

The present invention relates to devices forming the pivotal connections between cooperating members, such for example as the base and cover of a room thermostat.

An object of the invention is to provide an improved, inexpensive hinge construction, which has relatively few parts.

Another object of the invention is to provide a hinge construction, in which the main members cooperate with each other to form their own pivotal interconnection, and in which such members also hold themselves in appropriate assembled relation.

A further object of the invention is to provide a unit having components pivotally interconnected by a hinge device, in which one of the components, by itself, serves to secure the hinge device in assembled relation.

Still another object of the invention is to provide a thermostat unit having an improved hinge connection between its base and overlying housing.

Yet a further object of the invention is to provide a hinge construction which is capable of holding the hinge parts in open position, without tending to move such parts following their placement in closed position.

This invention possesses many other advantages, and has other objects which may be made more clearly apparent from a consideration of one embodiment of the invention. For this purpose there is shown a form in the drawings accompanying and forming part of the present specification. The form will now be described in detail illustrating the general principles of the invention; but it is to be understood that this detailed description is not to be taken in a limiting sense, since the scope of this invention is best defined by the appended claims.

Referring to the drawings:

Figure 1 is a pictorial, isometric representation of an articulated thermostat in open position;

Fig. 2 is an isometric projection of the hinge construction itself, with its main parts in relatively open position, as seen when looking toward the device from the front and upper left side of Fig. 1;

Fig. 3 is an exploded, isometric projection of the hinge construction, as seen when looking toward the device from the front upper right side of Fig. 1;

Fig. 4 is a section through the hinge device in open position, assembled to the thermostat base and housing, taken along the plane 4—4 on Fig. 2;

Fig. 5 is an isometric projection of the hinge structure, as seen from the rear of Fig. 2; and

2

Fig. 6 is a section taken along the plane 6—6 on Fig. 4.

The hinge construction exemplifying the invention is illustrated in Fig. 1, as applied to a thermostat, which includes a base 10 and an overlying housing, plate or cover 11. The base may have a plurality of holes 12 through its bottom portion, through which suitable fastening elements, such as screws (not shown), may pass in securing the thermostat to a wall or post (not shown). The upper end of the housing 11 is preferably pivoted to the upper end of the base 10, while its lower end is releasably secured to the base, to hold the housing in closed position adjacent the base. To accomplish this last-mentioned purpose, a spring latch 13 is attached to the lower end of the housing for engagement behind a suitable catch or lug 14 formed at the lower portion of the base.

As disclosed in Fig. 1, the housing or cover 11 contains a suitable thermometer 15 for indicating room temperature; thermostat elements 16, whose temperature operating range can be varied by a rotatable dial 17, which may be manually manipulated by a knurled flange 18; and a switch 19 for selectively controlling the operating or inoperative condition of the thermostat.

As aforementioned, the housing 11 is hingedly connected to the base 10. The hinge structure is formed primarily by a first hinge plate 20 secured to the base and a second hinge plate 21 secured to the housing.

To attach the hinge plate 20 to the base, the latter is provided with a pair of spaced parallel slots 22 and also with a hole 23 between the slots having an upper countersunk portion 24. The body 25 of the hinge plate 20 extends part way across the base 10, and has a countersunk central head 26 seating within the countersunk portion 24 of the base. A pair of generally parallel legs 27 at the ends of the body 25 extends through the base slots 22 to the lower surface 28 of the base, where the legs are inturned toward one another to form feet 29 snugly engaging the lower base surface, thereby securing the plate 20 to the base 10.

The base hinge plate 20 further includes an outwardly directed midsection or flange 30 integral with the body 25, and substantially at right angles thereto. Spaced arms 31, integral with the midsection 30, extend generally parallel to the body 25 of the plate. These arms are provided at the outer portions of the midsection 30, and have forearms 32 extending outwardly in opposite directions beyond the ends of the midsection 30. Fingers 33 extend outwardly beyond

the forearms and above shoulders 34 at the ends of the forearms.

An intermediate tongue 35 also projects from the midsection between the arms 31. This tongue is separated from the latter by suitable notches 36, to enable it to assume an upwardly and outwardly inclined position with respect to the body 25.

It is to be noted that the hinge member 20 just described is in one piece, and that it can be made from sheet metal, allowing its elements to be bent readily with respect to each other. This hinge member has pivotal connection with the hinge member or plate 21 secured to the housing 11. The latter plate 21 includes a body 37 integral with a curved bracket 38 substantially at right angles thereto. The bracket 38 is suitably attached, directly or indirectly, to the inner side of housing 11. In Figs. 2 and 3, this bracket is broken away.

The hinge plate 21 includes the main body portion 37 extending across the housing 11. Parallel arms 39 are disposed at right angle to the body portion, and are integral with its ends, extending toward the upper end wall 11a of the housing. These arms each have a relatively deep notch 40 and an adjacent relatively shallow notch 41 communicating with one another. In effect, the notches form upper and lower ledges or projections 42, 43 on the arms, which extends toward the upper end wall 11a of the housing 11. For the purpose of avoiding interference with the tongue 35 on the other hinge member 20 during movement of the parts, the main body portion 37 may be provided with a suitable recess 44.

When the hinge structure is assembled, the outwardly directed fingers 33 on the base hinge member 20 are inserted within the shallow notches 41 in the housing hinge member 21. It is to be noted that the fingers extend completely through such notches, and that the shoulders 34 are disposed within and adjacent the inner surfaces of the arms 39. Relative transverse movement between the hinge members 20, 21 is thereby prevented to any substantial extent, since such movement causes one or the other of the shoulders 34 to engage an adjacent arm 39 and forestall endwise movement of the fingers 33 from the shallow notches 41. Movement of the fingers through the open end of the shallow notches is prevented by the top wall 11a of the housing, which extends across the open ends of the notches adjacent their projections 42, 43, and, in effect, forms a closure for them.

It is evident that the disposition of the fingers 33 in the notches 41, and their confinement between the arms 39 and the housing wall 11a, form a pivotal or articulated connection between the main hinge members 20, 21, and, consequently, between the thermostat base 10 and housing 11. It is also desired to maintain the housing in open position at times, as depicted in Fig. 1, and yet avoid the presence of any force tending to move the housing from its closed position adjacent the base. To accomplish this objective, a leaf spring 45 is disposed within the housing unit plate 21, extending across the plate substantially at right angles to its body portion 37. The spring is bowed toward the tongue 35 of the other plate 20. The corners of the leaf spring 45 are notched to provide outwardly directed lugs or projections 46 fitting within the deep notches 40 in the plate arms 39, and also shoulders or abutments 47 engageable with the inner surfaces of the arms

39, to prevent substantial endwise movement of the leaf spring.

The upper wall 11a of the housing confines the spring 45 in the deep notches 40 by closing their open ends, in the same manner as it confines the hinge fingers 33 within the shallow notches 41. In other words, the upper wall 11a serves the double purpose of holding both the spring 45 and fingers 33 in their respective notches, assisting materially in maintaining the entire construction in appropriate assembled relation.

The projecting tongue 35 of the base hinge plate 20 is relatively movable transversely across the adjacent bowed face of the leaf spring 45 as the housing 11 is swung between open and closed position with respect to the base 10. When in substantially fully opened position, the tongue 35 does not engage the spring 45. However, partial movement of the housing 11 toward the base 10 causes the spring 45 to engage the tongue 35, the latter element then tending to straighten the spring against its resisting spring force, which provides resistance to movement of the housing to closed position. This position is shown in Fig. 4. However, sufficient force can be exerted to move the housing against this force to closed position. During this movement, the tongue 35 wipes transversely across the spring 45, and in so doing, first straightens the spring and then allows it to reassume its initial bowed condition. When the housing 11 approaches the base 10, the tongue 35 engages the spring 45, but lightly, or may be disengaged entirely therefrom. Accordingly, no spring force is present tending to move the housing to open position. When the housing is in open position, as shown in Figs. 1 and 4, the tongue is bearing fully against the spring, which exerts sufficient force to hold the housing in elevated position.

The tongue and spring arrangement thus provide for automatically holding the housing 11 in open position, while still eliminating any tendency for the housing to be shifted from its closed position.

The inventor claims:

1. In a hinge structure: a first plate having a pair of arms extending at right angles of the ends of the plate, and in the same direction, each arm being provided with a shallow notch and a deep notch; a second plate having a pair of oppositely directed fingers pivotally mounted in said shallow notches; a spring extending across said first plate, the ends of said spring being received within said deep notches; means on said second plate cooperating with said spring to control relative movement between said plates; and means for retaining said fingers and said spring in their respective notches.

2. In a hinge structure: a first plate having a pair of arms extending at right angles of the ends of the plate, and in the same direction, each arm being provided with a shallow notch and a deep notch; a second plate having a pair of oppositely directed fingers pivotally mounted in said shallow notches; a spring extending across said first plate, the ends of said spring being received within said deep notches; means on said second plate cooperating with said spring to control relative movement between said plates; and a housing secured to said first plate and extending across the open ends of said notches to retain said fingers and spring in their respective notches.

3. In combination: a base having slots therein; a housing adapted to be disposed in closed relation over said base; a first plate secured to

said housing and having a pair of arms extending at right angles of the ends of the plate, and in the same direction, each arm being provided with a shallow notch and a deep notch; a second plate having legs extending into said base slots, said second plate having a pair of oppositely directed fingers pivotally mounted in said shallow notches; a spring extending across said first plate, the ends of said spring being received within said deep notches; means on said second plate cooperating with said spring to control relative movement between said plates; said housing extending across the open ends of said notches to retain said fingers and springs in their respective notches.

4. In combination: a base having slots therein; a housing adapted to be disposed in closed relation over said base; a first plate having a pair of arms extending at right angles of the ends of the plate, and in the same direction, each arm being provided with a shallow notch and a deep notch; a second plate having legs extending into said base slots, said legs terminating in feet disposed against the bottom of said base; said second plate having a pair of oppositely directed elements, each element including an outer finger pivotally mounted in said shallow notch and a shoulder adjacent said finger engageable with an arm to prevent substantial endwise movement of said finger from said shallow notch; a spring leaf extending across said first plate, the ends of said spring being received within said deep notches; said housing extending across the open ends of said notches to retain said fingers and springs therein; and means on said second plate cooperating with said spring leaf to control relative movement between said plates.

5. In combination: a base; a housing cooperating with the base; a pair of hinge members respectively rigidly fastened to the housing and the base; each of said members having spaced

projections, the spaced projections of one member being hingedly connected respectively to the spaced projections of the other member, the axis of the hinged connections falling along a common line; a leaf spring extending between the spaced projections of one of the members and carried thereby; said leaf spring having relatively wide parallel surfaces and narrow edges; the wide surfaces of the spring being spaced from the axis; and an abutment rigidly fastened to the other member and between its two spaced projections, said abutment engaging the leaf spring on one wide surface thereof and forming a rest for the said one member yieldingly to maintain the housing and the base in open hinged position; the place of contact between the abutment and the spring being spaced from the hinge axis so that when the hinge is being closed, said rest slides transversely off the said wide surface.

WILBERT C. BUESCHER.
